UNITED STATES PATENT OFFICE.

HERBERT HACKNEY, OF TOPEKA, KANSAS, ASSIGNOR TO THE HACKNEY STEAM BOILER IMPROVEMENT COMPANY, OF ILLINOIS.

FEED-WATER PURIFIER FOR STEAM-BOILERS.

SPECIFICATION forming part of Letters Patent No. 410,413, dated September 3, 1889.

Application filed April 2, 1889. Serial No. 305,765. (No model.)

To all whom it may concern:

Be it known that I, HERBERT HACKNEY, a citizen of the United States, residing at Topeka, in the county of Shawnee, State of 5 Kansas, have invented certain new and useful Improvements in Feed-Water Purifiers for Steam-Boilers, of which I do declare the following to be a full, clear, and exact description, reference being had to the accompanying drawings, forming part of this specification.

A serious difficulty encountered in the use of steam-boilers, particularly in sections of the country where the water is strongly impregnated with lime, chemically or mechanically sustained in solution, is due to the fact that a hard scale or crust is formed upon the surface and tubes of the boilers by reason of the deposition of the lime, and as well also of 15 other impurities from the water, so that the cleaning of the boilers becomes a matter of such frequent necessity as to cause serious expense and inconvenience.

The primary object of my invention is to 25 provide improved means whereby the delivery of the feed-water to the boiler shall be effected in such manner that the impurities in the water, notably the carbonate of lime, shall be deposited therefrom within suitable 30 receptacles provided for the purpose before the water is delivered into such part of the boiler as to contact with the walls of the tubes or boiler-surface proper.

A further object of my invention is to secure a more effective circulation of the water 35 within the boiler.

To this end my invention consists in the novel features of construction hereinafter described, illustrated in the accompanying 40 drawings, and particularly pointed out in the claims at the end of this specification.

Figure 1 is a view in vertical longitudinal section on line $x-x$ of Fig. 2. Fig. 2 is a view in vertical cross-section on line 2-2 of Fig. 1. 45 Fig. 3 is an enlarged detail perspective view of one of the end chambers for the sediment-troughs. Fig. 4 is a similar detail perspective view of the opposite end chamber of the sediment-troughs. Fig. 5 is a view in vertical 50 cross-section showing a modified construction

of sediment-trough. Fig. 6 is a detail view showing a modified arrangement of delivery and discharge chambers.

A designates the body of the boiler, through which extend the usual flues a , and B denotes a mud-drum, that communicates by the discharge-pipe b with the lower portion of the body of the boiler. Across the front end of the boiler A extends the delivery end chamber C, and across the rear end of the boiler extends a somewhat similar discharge-chamber D, each of these chambers being suitably sustained, as by brackets 5, from the walls of the boilers. The inner side of each of the end chambers C and D is by preference 65 provided with a series of ribs or flanges E, corresponding in shape to the cross-section of the sediment-troughs F, which extend from end to end of the boiler and have their extreme ends fitted within and bolted to the flanges E of the end chambers. These sediment-troughs F comprise the upwardly and outwardly flaring walls, the lower portions of these walls being brought very near together and united with the upper edge of the expanded pockets f , formed, by preference, of approximately cylindrical shape.

By reference more particularly to Fig. 3 of the drawings it will be seen that the chamber C is provided opposite the sediment-troughs F with openings c , corresponding, preferably, with the spaces between the flaring walls of the troughs, while the chamber D at the opposite end of the boiler is provided with openings d , that communicate simply with the pockets f of the troughs. Into the chamber C leads a suitable feed-water pipe G, through which the feed-water of the boiler will be delivered, and from this chamber C also lead suitable circulating-pipes H, that serve to connect this chamber with the mud-drum B. From end to end of the bottom of the mud-drum B extends a false bottom B', that is perforated adjacent its lower edges, the purpose of this false bottom being to aid in collecting the sediment that is precipitated within the drum, and at one end of the drum will be provided a suitable blow-off pipe B², by the opening of which the sediment in the drum can be removed from time to time.

From the foregoing construction it will be seen that when the feed-water is delivered into the chamber C by the delivery-pipe G it will pass through the openings *c* of this chamber into and along the upper portions of the sediment-troughs F from front to back of the boiler. As the comparatively cold water is thus introduced and mingles with the warmer water within the upper portion of the boiler, it will be diluted thereby, and the carbonate of lime held in suspension by the carbonic acid of the water will, by reason of this dilution with the water of higher temperature and comparatively free from carbonic acid, be caused to settle upon the inclined faces of the sediment-troughs and to deposit thence into the pockets of these troughs. This incoming supply of water will, as it becomes heated, rise and flow over the edges of the sediment-troughs and mingle with the main volume of water within the boiler. My object in extending a series of sediment-troughs from end to end of the boiler and in connecting these troughs with a suitable chamber C, through which the feed-water is delivered, is to enable the delivery of the feed-water into the body of the boiler to be effected over as wide an area as possible, so that a more perfect deposition of the impurities upon the sediment-troughs may be secured; and my purpose in connecting the end chamber C with the upper portion only of the delivery-troughs is to insure that the delivery of the feed-water will cause as little disturbance of the sediment within the troughs as possible. For like reason the discharge-chamber D is connected only with the lower portions or pockets of the sediment-troughs, so that as the feed-water is delivered into the upper portions of these troughs there will be no circulation through the pockets tending to disturb the deposit of sediment therein. When, however, it is desired to remove from the pockets *f* of the sediment-troughs the deposit therein collected, it will only be necessary to open the blow-off pipe D', that extends from the end chamber D, thereby causing the sediment within the pockets of the troughs F to pass into the end chamber D, and thence out of the boiler. It will be seen also that by reason of the connection of the mud-drum B with the delivery end chamber C by means of the circulating-pipes H a free circulation of the water from the upper part of the boiler through the mud-drum is secured, and in practice it will be found that a much more effective circulation is obtained by reason of the wide distribution of the incoming volume of feed-water by means of the delivery end chamber C and the series of sediment-troughs.

In Fig. 5 of the drawings is illustrated a modified form of sediment-trough—that is to say, the sediment-trough proper is shown as provided with V-shaped false bottoms F' and F'', (one or more may be used,) which extend from end to end of the trough, and are suitably sustained in position either by brackets

extending from the trough or by flanges projecting from the end chamber, to which the troughs will be attached. These V-shaped troughs have long perforations or channels *f'* at their bottoms, through which the sediment will pass from one trough to the trough beneath, and finally into the sediment-pocket *f*. My purpose in thus providing the main sediment-trough with false bottoms, either one or more in number, is to expose a larger surface for collecting the sediment from the water and delivering it into the sediment-pockets.

In Fig. 6 of the drawings is shown a modified manner of attaching the sediment-troughs to the delivery and discharge chambers. In this construction the discharge-chambers C and D are formed together, constituting, in fact, a single box divided by a partition-wall or diaphragm R, that extends from end to end of the box and serves to separate the delivery-chamber C from the discharge-chamber D. In this construction the delivery-chamber C will be provided with openings communicating with the upper portion of the troughs, and the discharge-chamber D will be provided with openings communicating with the sediment-pockets *f* of the troughs, and into the delivery-chamber C will lead a suitable feed-water pipe G and suitable circulating-pipes H, that will connect the chamber C with the mud-drum B. When this construction is followed, the ends of the sediment-troughs F at the back of the boiler will be closed, the delivery-chamber D not being then employed.

It will be readily understood that by opening the blow-off pipe attached to the discharge-chamber D in this last form of apparatus the sediment deposited within the pockets *f* can be withdrawn into the discharge-chamber and thence through the blow-off pipe.

Having thus described my invention, what I claim as new, and desire to secure by Letters Patent, is—

1. The combination, with a steam-boiler, of a series of open sediment-troughs extending from end to end of said boiler, a delivery-chamber connected to said troughs and communicating therewith, a discharge-chamber connected to said troughs and communicating therewith, a feed-water-delivery pipe leading into said delivery-chamber, and a blow-off pipe leading from said discharge-chamber, substantially as described.

2. The combination, with a steam-boiler, of a series of troughs having upwardly-expanded walls, and having sediment-pockets communicating with the contracted portions of said walls, and suitable means for delivering the feed-water into said troughs, substantially as described.

3. The combination, with a steam-boiler, of a series of sediment-troughs having upwardly-expanded walls, and having sediment-pockets connected with the contracted portions of said walls, a delivery-chamber at one end of

said troughs, a discharge-chamber at the opposite end of said troughs, a feed-water-delivery pipe communicating with said delivery-chamber, and a blow-off pipe communicating with the discharge-chamber, substantially as described.

4. The combination, with a steam-boiler, of a series of sediment-troughs having expanded upper walls, and having sediment-pockets connected to the contracted bottoms of said walls, a delivery-chamber connected to the front ends of said troughs and having openings communicating with the upper portion of said troughs, a discharge-chamber connected with the opposite ends of said troughs and having openings communicating with the sediment-pockets, a feed-water pipe leading into said delivery-chamber, and a blow-off pipe leading from said discharge-chamber, substantially as described.

5. The combination, with a steam-boiler, of a series of sediment-troughs, a delivery-chamber connected with the ends of said troughs, and a discharge-chamber connected with the opposite ends of said troughs, said delivery and discharge chambers being provided with flanges E for sustaining said troughs, substantially as described.

6. The combination, with a steam-boiler, of a series of sediment-troughs extending from end to end of said boiler in its upper portions, suitable means for delivering the feed-water into said troughs, suitable means for removing the sediment from said troughs, a mud-drum communicating with the boiler at its lower portion, and suitable circulating-

pipes connecting said mud-drum with the upper portion of the boiler, substantially as described.

7. The combination, with a steam-boiler, of a series of sediment-troughs extending from end to end thereof in its upper portion, a delivery-chamber connected to said troughs and having openings communicating therewith, a discharge-chamber connected to the opposite ends of said troughs and having openings communicating therewith, a mud-drum, a pipe connecting said mud-drum with the lower portion of the boiler, and suitable circulating-pipes leading from said mud-drum to the delivery-chamber, substantially as described.

8. The combination, with a steam-boiler, of a sediment-trough having upwardly-expanded walls, and having a sediment-pocket connected with said walls at their contracted portions, and suitable means for delivering the feed-water to said trough, and suitable means for withdrawing the sediment therefrom, substantially as described.

9. The combination, with a steam-boiler, of a sediment-trough having upwardly-expanded walls, and having a sediment-pocket communicating with the lower contracted portion of said walls, and having also a V-shaped false bottom, and suitable means for delivering the feed-water into said trough, and suitable means for withdrawing the sediment therefrom, substantially as described.
